UNITED STATES PATENT OFFICE.

ANDREAS WILHELM SCHWARZLOSE, OF BERLIN, GERMANY.

LOCK MECHANISM FOR AUTOMATIC FIREARMS.

932,183.

Specification of Letters Patent. Patented Aug. 24, 1909.

Application filed September 3, 1907. Serial No. 391,184.

To all whom it may concern:

Be it known that I, A. W. SCHWARZLOSE, a subject of the German Emperor and resident of Berlin, Germany, have invented certain new and useful Improvements in Lock Mechanisms for Automatic Firearms, of which the following is a specification.

This invention relates to improvements in lock mechanism for fire arms and is especially adapted for use in connection with fire arms of the automatic type.

The main object of the invention is to provide a lock mechanism which will offer absolute security against accidental discharge of the weapon and which will simplify and render the mechanism more effective than constructions heretofore used. The main object of providing absolute security is realized by the provision of a mechanism wherein the usual main spring for actuating the hammer is not normally under tension and is therefore incapable of actuating the hammer until said spring is placed under tension.

A further object of the invention, when the same is applied to fire arms having a slidably mounted barrel, is to provide means carried by the barrel and adapted to coöperate with the hammer and be actuated by the trigger for the purpose of cocking and releasing the hammer.

The invention comprises other features which will be more fully described in connection with the accompanying drawings and will be more particularly pointed out and ascertained in and by the appended claim.

In the drawings: Figure 1 is a sectional view of an automatic fire arm provided with a slidably mounted barrel and illustrating the device of my invention in connection therewith. Fig. 2 is a similar view showing the parts in a changed position. Fig. 3 is a front elevation of the fire arm shown in Fig. 1. Fig. 4 is a bottom plan view of the barrel detached. Fig. 5 illustrates plan and side views respectively of an improved form of sear. Fig. 6 shows front and side views of the hammer detached. Fig. 7 is a plan view of tension-link or element. Fig. 8 illustrates

a modified form of the invention with parts broken away. Fig. 9 illustrates a further modification of the invention. Fig. 10 is a vertical sectional view of a still further modification of my invention.

55

Like characters of reference designate similar parts throughout the different figures of the drawings.

The device of my invention is specifically shown in accompanying drawings in connection with an automatic fire arm provided with a slidably mounted barrel but it will be understood that I do not wish to be limited to the specific form shown.

Referring to the forms shown in Figs. 1 to 7 inclusive 1 designates the handle of the pistol in which is slidably mounted a common form of cartridge magazine 32 adapted to be held in place by a catch 16. Said catch 16, as shown, is pivotally mounted at 17 and is provided with a shoulder 18 which engages the bottom wall of the magazine to hold the same in place. A main spring, or the equivalent thereof, is indicated at 11 and consists as shown of a flat strip of spring metal. Said spring is provided between its ends with a fulcrum which may conveniently be formed by a flat surface 33 on the catch 16. The spring 11 is operatively associated with a hammer, indicated at 6, and preferably a lug 10 is formed on said hammer and is disposed in a manner to engage the upper end of said spring. In the form of hammer shown the same is pivoted at 7 and is provided on its upper end with a firing pin 8. Said hammer is adapted to be actuated and released by a sear, herein after described, and to this end said hammer is preferably provided with a lug 22 which as shown projects laterally from the hammer. A barrel abutment 5 is located at the breech and is provided with an opening 9 to accommodate the firing pin 8.

The barrel 2 herein shown is slidably mounted and its construction and the construction of parts associated therewith are described in detail in my co-pending application filed August 21, 1907, Serial No. 389,560 and will not be described in detail in this case as they form no feature of the

95

present invention. Generally speaking the barrel 2 is reciprocated outwardly by the projectile when the cartridge is discharged and is returned, to the position shown in Fig. 1, by a spring 4. A trigger 26 is pivotally mounted at 25 and is provided with a sear actuating member 28. The trigger 26 is held in a normal position by a spring 27. Said trigger 26 is adapted to coöperate with a tension member, which will be hereinafter more fully described, and is provided with a locking portion 34 adapted to be engaged by said member. Said barrel is provided with means the function of which is to cock the hammer 6 upon the return movement of the barrel and be actuated by the trigger to release the hammer when said barrel has returned and the trigger is actuated for firing a new shell. Referring to the specific form shown, 35 designates a sear which is pivotally mounted at 20 upon the barrel 2. 19 designates the hammer actuating end of the sear which lies within a groove formed in an extension 36 of the barrel 2. A spring 21 is disposed in a socket 37, formed in the sear, and normally tends to hold the hammer actuating end in the path of the lug 22. In order to render engagement between the sear and the hammer more effective the former may be provided with a projection 38. The trigger actuated end of the sear is indicated at 23 and is provided with a lug 24 which projects into the path of the sear actuating member 28. The parts are so disposed that when they are in the position shown in Fig. 1 the lug 24 will be located in such a manner that when the member 28 is swung rearwardly it will engage the wedge shaped forward end of the lug 24 and swing the latter inwardly thereby causing the other end of the sear 19 to swing outwardly out of engagement with the lug 22.

A tension member 14 is shown and the same is pivotally mounted at 15. At its upper end said tension member is provided with a trigger locking portion 39 of complementary formation with and adapted to coöperate with the locking portion 34 of the trigger for the purpose of locking the same when the parts are in the position shown in Fig. 1. Said tension member coöperates with the spring 11 for the purpose of placing the same under tension but it will be understood that in the normal position shown in Fig. 1 the spring is free and not under tension. In this form of the invention the member 14 is connected with the spring 11 by a yoke shaped link 12 which is looped about the spring 11 and is pivotally secured at 13 to the member 14. Said link 12 may conveniently be held in engagement with the spring 11 by a suitable extension which is shown formed on the catch 16.

The operation is as follows: Assuming that the parts are in the position shown in

Fig. 1 it will be seen that the trigger 26 is locked by the tension member 14 and that the hammer 6 is shown in a cocked position. To fire the cartridge the user will grasp the weapon by inserting the fore-finger through the trigger guard and placing it upon the trigger and by grasping the tension member 14 with the remaining fingers. The tension member 14 will first be retracted as shown in Fig. 2 which operation will serve to simultaneously tension the spring 11 and release the trigger 26. This operation however will not fire the cartridge as it will be necessary for the user to retract the trigger to release the hammer which is now under stress. When the trigger is retracted the member 28 will force the lug 24 inwardly thereby throwing the lug 38 out of engagement with the lug 22 to permit the spring 11 to act upon the hammer. The projectile discharged from the cartridge will carry the barrel 2 outwardly to the limit of its travel thereby releasing engagement between the lug 24 and the member 28 and permitting the spring 21 to force the lug 38 into the path of the lug 22, which is now rearwardly disposed with respect to the lug 38. The tension member and trigger will be released by the user so that the spring 11 will not be under tension and the spring 4 will return the barrel 2 to a starting position. As the lug 38 approaches the lug 22, upon return movement of the barrel 2, it will engage the same and cock the hammer in the position shown in Fig. 1.

In the form shown in Fig. 8 the spring 11 is interposed between a lug 10 on the hammer 6 and a catch 16'. Said catch is secured at 17' and is provided with a shoulder 18' for holding the magazine in position. A strut-bar 30 engages the spring 11 between its endwise mountings and seats in a recess in the tension member 14. It will be obvious from the foregoing that as the tension member 14 is retracted it will place the spring 11 under tension in the manner shown in dotted lines.

In the form shown in Fig. 9 the spring 11 is mounted at one end in a recess of the catch 16'' and engages at its other end a lug 10' mounted on the rear side of the pivot 7 of the hammer 6. In this form of the invention the tension member 14' is located on the rear side of the handle and is pivotally connected thereto at 15'. A lug 31' is provided on the tension member 14' and is adapted to engage the spring 11 and tension the same in the direction of the arrow.

In Fig. 10 the hammer actuating spring 11 is mounted upon a movable part 14'' at 31, which part is pivoted at 15''. Spring 11 actuates a reciprocating hammer 32' mounted in a way 33' in the part 34' and said hammer is provided with a firing pin 35' and a lug 38'. A spring actuated sear

36' is pivotally mounted at 37' and engages said lug 38' and is also adapted to be actuated by an extension 28' of the trigger 26.

I claim:

- 5 An automatic fire arm comprising in combination, a slidably mounted barrel provided with hammer cocking means, a trigger adapted to cooperate with said means to throw the same into a non-engaging position, a hammer adapted to be cocked by said means, a main spring normally free and en-

gaging said hammer, and a tensioning member normally locking said trigger and serving when actuated to free the same and tension said spring.

15

In testimony whereof I have hereunto set my hand in presence of two witnesses.

ANDREAS WILHELM SCHWARZLOSE.

Witnesses:

WOLDEMAR HAUPT,
ARTHUR SCHROEDER.
